UNITED STATES PATENT OFFICE.

JOSEPH OSTAND, OF CINCINNATI, OHIO.

AERIAL NAVIGATION APPARATUS.

987,819.

Specification of Letters Patent. Patented Mar. 28, 1911.

Application filed March 21, 1910. Serial No. 550,662.

To all whom it may concern:

Be it known that I, JOSEPH OSTAND, a subject of the King of Roumania, residing at Cincinnati, in the county of Hamilton and State of Ohio, have invented certain new and useful Improvements in Aerial Navigation Apparatus, of which the following is a specification.

It is the object of my invention to provide an aerial navigation apparatus embracing an inflated buoyancy-member having a parachute-member received thereabout and so arranged that said members may be adjusted to relative elevation for permitting escape of air pressure between the two members or for causing the two members to come into intimate contact in order to retain the air-pressure between the same.

My invention consists further in providing a plurality of inflated buoyancy-bags arranged about a carried member, shown as a tent-structure, the latter having an inflated buoyancy-bag immediately thereabove, the said structure and last-named bags having connection with said inflated buoyancy-member and parachute-member for receiving support from said members and controlling the relative elevations of said members, said members being arranged to be sent up into the air in advance of said structure and accompanying bags. The said connection is obtained by means of flexible connections leading from said buoyancy-member and parachute-member to said structure, upon which means are provided for manipulating said flexible connections for determining the distance between said structure and said first-named members and for controlling the relative elevations of said members.

My invention is also arranged to embody a kite of novel form having flexible connection with said tent-structure in novel manner.

The invention will be further readily understood from the following description and claims, and from the drawings, in which latter:

Figure 1 is a rear elevation of my improved device, partly broken away, showing the flexible connections for the upper buoyancy and parachute members and the kite partly broken away, the said buoyancy and parachute members and kite being arranged in practice to be at considerable elevation above the carried structure and its accompanying inflated bags. Fig. 2 is a bot-

tom view of my improved device, with the kite omitted. Fig. 3 is a horizontal section of my improved device taken on the line $z-z$ of Fig. 1, with the brackets for the propeller-shafts partly broken away. Fig. 4 is a detail in vertical section showing the contacting means between the upper inflated buoyancy member and the parachute member in contacting relation in full lines, the former being also shown in dotted lines for illustrating the contacting means in separated relation. Fig. 5 is a detail in vertical section on the line $y-y$ of Fig. 3, partly broken away, showing the manner of connecting the intermediate inflated bag to the tent-structure, and of connecting the parts of the tent-structure; and, Fig. 6 is a side elevation partly in section, of one of the inflated bags.

1 represents the upper inflated buoyancy-member, shown as a bag, which is surrounded by a band 2 to which suspending cords 3 are secured, which merge into suspending cords 3', the lower ends of the latter being connected to a ring 4, from which flexible connections 5 depend.

6 is a wind buoyancy member, and may be in the form of a parachute, having a central aperture 7 through which the upper end of the bag 1, which is the upper bag of my improved device, is received, the parachute-member 6 normally contacting with the bag, the parts being so proportioned however, that the bag will not pass through the aperture. Thus the wall of the aperture may comprise a stiffening-ring 8 arranged to rest on a stiffening-ring 9 secured to the inflated bag 1, the stiffening-ring 8 normally resting on the stiffening-ring 9 for closing the opening in the parachute-member against upward passage of air therethrough.

Means are provided which will be more fully hereinafter explained by which relative elevation may be had between the upper inflated bag 1 and the parachute 6, so that the bag will fill the central aperture for forming a buoyancy-chamber 10 under the parachute, between the bag 1 and the parachute, or so that a space 11 will be provided between the wall of the aperture and the upper inflated bag for permitting the air or pressure to be relieved through said space. When the bag closes said aperture, the existence of wind or air pressure under the 105 parachute in said buoyancy-chamber will aid 110 in supporting the carried parts. Upon ex-

istence of sufficient wind pressure in said buoyancy-chamber a raising of said carried parts will result. The said buoyancy-chamber will also retard the descent of the device, if desired. If more pressure is present under the parachute-member than is desired, the parachute-member is raised or the upper bag lowered, the one relatively to the other, for providing space between the same through which the pressure may be relieved. Currents of air passing into said buoyancy-chamber 10 under said parachute aid materially in causing raising of the device. Flexible connections 12 connect with the outer edge of the parachute-member, preferably by means of supplemental suspending-cords 13 and 13'.

16 is a kite which comprises a flat frame 17, disks 18 at the sides of the frame having connection with said frame by springs 19, and a tail 20 suspended from said frame 17 by links 21. The flat frame, disks and tail may be respectively constructed of a framework, indicated in dotted lines, over which canvas is stretched and then painted. A flexible connection 22 connects with supplemental connections 23 secured to the kite.

The upper inflated bag, the parachute and the kite are in practice arranged to be in the air at considerable elevation above the carried member and accompanying inflated bags hereinafter mentioned, the elevations of said upper bag, parachute and kite being controlled from said carried member. The kite is intended for use when traveling in the direction of the wind. When not in use it is arranged to be received in the carried member.

26 is a carried member shown as a tent-structure comprising a floor 27 which comprises extensions 28 29 forming platforms at the respective sides thereof, a central tube 30 passing through the floor and being secured thereto and extending upwardly therefrom. A ring 31 is secured to the upper end of the tube. Stanchions 35 pass through holes 32 in the ring 31 at their upper ends and have nuts 33 34 thereabout at top and bottom of the ring and their lower ends are received through holes 37 in the floor, nuts 38 and 39 being received about the threaded lower ends of said stanchions respectively above and below the floor for supporting said floor and stanchions. There is a suitable covering 40 received about the stanchions for forming a closed structure, having a chamber 41, this covering preferably comprising widths of canvas, properly waterproofed, having loops 42 received about the stanchions. At each side of the structure this covering takes the form of a flap 43 which may be opened or closed and is arranged for ingress into or egress out of the structure. The lower ends of these flaps if desired may be supported on posts 44 ex-

tending upwardly from the platforms, or the same may be secured in closed relation by means of buttons 45.

Inflated buoyancy bags 51 52 53 54 are located about the tent-structure. Each of 70 these last-named buoyancy bags has flexible connections 55 secured thereto, as through the medium of a band 56 surrounding said bag, these flexible connections having connection at their lower ends with a ring 57 75 which has adjustable connection with a runway 58. These runways are parts of the front and rear extensions 59 60 of the floor formed preferably of rods and braces therefor. The rings 57 may be suitably secured 80 lengthwise of said runway by means of securing ropes 61. By this means I am enabled to change the lateral positions of the inflated bags located about the tent-structure to compensate for the load on the floor. 85

65 is an intermediate inflated buoyancy bag with which flexible connections 66 connect, as through the medium of a band 67 received about said buoyancy bag. The lower ends of each pair of these flexible connections merges into a flexible connection 66', these flexible connections 66' passing through the tube and being connected at their lower ends to cross-bars 68 which are located crosswise on the lower face of the 95 floor.

71 72 and 73 74 are screw propellers which are arranged tandem in pairs at the respective sides of the carried member, the propellers of the respective pairs being secured 100 to shafts 75 76 respectively mounted in bearings 77 78 in brackets 79 80 extending laterally from the platforms.

81 is a motor of suitable construction, preferably a reversible internal combustion 105 motor suitably secured to the floor.

82 is a counter-shaft arranged to be driven from the motor by means of a sprocket-chain 83 received about the sprocket-wheel 84 secured to said countershaft and a sprocket-wheel 85 secured to the motor-shaft. A sprocket-chain 86 is received about a sprocket-wheel 87 loose on said countershaft and a sprocket-wheel 88 on the propeller-shaft 75. A clutch 89 is arranged to selectively connect the sprocket-wheel 87 to said countershaft or to disconnect the same therefrom, and is arranged to be operated by a lever 90 extending through the floor. A sprocket-chain 91 is received about a sprocket-wheel 92 loose on said countershaft and a sprocket-wheel 93 on the propeller-shaft 76. A clutch 94 is arranged to selectively connect the sprocket-wheel 92 to said countershaft or to disconnect the same therefrom, and is arranged to be operated by a lever 95 extending through the floor. By this means the propellers may be driven in one or the other direction, depending on the direction in which the motor is driven, and 130

each pair may also be selectively connected to or disconnected from the motor, as may be desired.

The countershaft 82 is preferably located 5 below the floor and the sprocket-chain 83 passes from the motor-shaft through an opening 96 in the floor to the sprocket-wheel on said countershaft. The sprocket-wheels on said countershaft are preferably 10 each connected with the countershaft through the medium of the clutch so that the propellers at either side of the tent-structure may be selectively brought into motion in order to govern the direction of movement of the device.

The flexible connections 5 connecting with the upper inflated bag are shown as four in number and the flexible connections 12 connecting with the parachute member are also 20 shown as four in number. These flexible connections are arranged to depend and connect with the carried member and to aid in supporting the same, and the relative elevations of said upper inflated member and 25 parachute member are also controlled from said carried member through said flexible connections. For accomplishing this the flexible connections 5 of the upper bag are received about pulleys 101 secured to the 30 extensions at each of the four sides of the floor, and extend across the bottom of the floor and pass about pulleys 102 and through apertures 103 in the floor to a spool 104.

35 The flexible connections 12 of the parachute are received about pulleys 105, secured to the extensions of the floor, and pass across the bottom of said floor and about pulleys 106 and through apertures 107 in 40 the floor and about a spool 108.

The spools 104 108 are mounted on a countershaft 109 which has a sprocket-wheel 110 thereon, a sprocket-chain 111 passing over said sprocket-wheel and a sprocket-wheel 45 112. The sprocket-wheel 112 is connected with and disconnected from the motor shaft by means of a clutch 113. The spool 104 is connected with said countershaft 109 and disconnected therefrom by means of a clutch 50 114, and the spool 108 is connected with and disconnected from said countershaft by means of a clutch 115. By these means suitable driving connections are obtained with either or both of the series of flexible connections 5 and 12, as may be desired.

55 Suitable means are also provided for maintaining the spools stationary. There is for instance a locating pin 116 in a bracket 117 secured to the floor which is received into suitable apertures in the flange 118 of the spool 104, and a locating pin 119 in said bracket received in suitable apertures in a flange 120 of the spool 108.

If it is desired to permit the upper inflated member and the parachute member to

simultaneously ascend or to cause approach between said members and the carried member, under control of the engine, the engine is operated in the desired direction and driving connections made with said spools for 70 paying out or winding up the flexible connections as may be desired. If it is desired to change the relative elevations of the upper inflated bag and the parachute member for providing the space 11 between the same, 75 the inflated bag may be drawn down or the parachute member be permitted to rise with relation to the upper inflated bag, or said space may be again closed by controlling said flexible connections.

80 The flexible connection for the kite passes to the floor of the structure about a pulley 123 linked to a pulley 121 on a flexible member 122 suitably secured at one end to the upper end of the tent-structure and at its 85 lower end to the lower part of the same, the pulley being accommodated on the flexible member according to the strain upon the same by the kite.

85 The buoyancy members heretofore described are above the floor of the device upon which the passenger or passengers or load to be carried are intended to be located. Under this floor I provide a central casing 126 shown in the form of a box, which is 90 suspended from a frame-work 127 shown constructed of bars and braces, this frame-work being suspended from the floor. At each corner of this frame-work an inverted inflated bag 128 is suspended. The lower 95 ends of these inverted inflated bags are also secured for controlling the positions of the same, as by means of brackets 129 which extend laterally from the box and have connection with the lower ends of said lower inverted inflated bags. The purpose of these lower inverted inflated bags and the box is to carry a supply of inflating substance and they serve to buoy the carried structure from below in case the same should alight on water. Suitable supporting wheels 130 are provided adjacent the bottom of the box. Ladders 131 are arranged to be suspended from the platforms for providing access thereto.

100 105 110 115 120 125 130 The inflated buoyancy members may be formed of tent-like halves having their ends of largest diameter presented toward each other, with the band surrounding the same located at the joint between said halves. Thus referring to Fig. 6 in which the inflated buoyancy bag 51 is shown as an exemplification of the construction of all of said bags, there are widths 132 132' of canvas connected by seams 133 133' the ends 134 134' of largest diameter of the respective halves 135 135' of said bag being connected by the surrounding band 56 by means of seams 136 136', the bag being properly waterproofed and made impervious to gas. The lower inverted buoyancy bags may be

formed similarly to the lower end of said buoyancy bag 51.

Having thus fully described my invention, what I claim as new and desire to secure by 5 Letters Patent is:

1. In an aerial navigation apparatus, the combination of an inflated buoyancy member, a parachute member spreading to substantially greater width than said inflated 10 buoyancy member for forming an air-buoyancy chamber between said parachute member and inflated buoyancy member, said parachute member being provided with an aperture in its top through which said inflated 15 buoyancy member projects upwardly, and means for controlling the relative elevations between said inflated buoyancy member and the wall of said aperture, substantially for the purpose described.
2. In an aerial navigation apparatus, the combination of an inflated buoyancy member, a parachute member spreading to substantially greater width than said inflated 20 buoyancy member for forming an air-buoyancy chamber between said parachute member and inflated buoyancy member, said parachute member being provided with an aperture in its top through which said inflated 25 buoyancy member projects upwardly, a carried member, flexible connections between said inflated buoyancy member and parachute member, and said carried member for supporting said latter member from said 30 first-named members, and means for controlling the operative lengths of said flexible connections between said carried member and said inflated buoyancy member and parachute member respectively for controlling 35 the relative elevations between said inflated buoyancy member and the wall of said aperture, substantially for the purpose described.
3. In an aerial navigation apparatus, the combination of an inflated buoyancy member, a parachute member spreading to substantially greater width than said inflated 40 buoyancy member and received about said inflated buoyancy member for forming a buoyancy-chamber between said inflated buoyancy member and parachute member, and means for controlling the continuity of 45 the wall of said buoyancy-chamber during maintenance of inflated condition of said inflated buoyancy member and the spread condition of 50 said parachute member for regulating the buoyancy-pressure therein, substantially for the purpose described.
4. In an aerial navigation apparatus, the combination of an inflated buoyancy member, a carried structure in the form of a tent-structure comprising a floor, a central tube, inclined stanchions between said floor and tube, a kite, a flexible connection therefor, securing means for said flexible connection 55 at the lower portion of said tent-structure, a

flexible member secured at its upper terminus adjacent to the upper end of said tube and stanchions and at its lower end to the lower end of said tent-structure, and of a length to form a loop extending substantially above said tent-structure, said flexible connection having slip connection with that portion of said flexible member farthest removed from said tent-structure, substantially as described. 70

5. In an aerial navigation apparatus, the combination of an inflated buoyancy member, a parachute member spreading to substantially greater width than the said inflated 75 buoyancy member for forming an air-buoyancy chamber between said parachute member and inflated buoyancy member, said parachute member being provided with an aperture in its top through which said inflated buoyancy member projects upwardly 80 to substantial extent, a carried member, a winding apparatus thereon, flexible connections between said respective inflated buoyancy and parachute members and said winding apparatus, said winding apparatus arranged for controlling the operative lengths of 85 said respective flexible connections for controlling the relative elevation between said inflated buoyancy member and said parachute member during maintenance of 90 inflated condition of said inflated buoyancy member and the spread condition of said 95 parachute member, substantially for the purpose described.

6. In an aerial navigation apparatus, the combination of an inflated buoyancy member, a parachute member, spreading to substantially greater width than said inflated buoyancy member for forming an air-buoyancy chamber between said parachute member and inflated buoyancy member, said parachute member being provided with an aperture in its top through which said inflated buoyancy member projects upwardly to substantial extent, a carried member, a propeller therefor, an engine for operating said propeller, winding apparatus on said carried member having operative connection with said engine, flexible connections between said respective inflated buoyancy and 110 parachute members and said winding apparatus, said winding apparatus arranged for controlling the relative elevation between said inflated buoyancy member and said 115 parachute member during maintenance of inflated condition of said inflated buoyancy member and the spread condition of said 120 parachute member, and means for selectively operatively connecting said propeller or said winding apparatus with said engine or 125 collectively operatively connecting said propeller and winding apparatus with said engine, substantially for the purpose described.

7. In an aerial navigation apparatus, the combination of a tent-structure comprising 130

- a floor, stanchions extending upwardly therefrom toward each other, and a covering about said stanchions for forming a tent-structure which tapers upwardly and 5 has a chamber thereunder, and a series of inflated bags located about said tent-structure and having lower ends which taper downwardly at the side of said upwardly tapering tent-structure, and adjustable connections 10 between said respective bags and said tent-structure for adjusting the lateral placement of said bags about said tent-structure, the adjacent sides of said inflated bags extending into the longitudinal projection 15 of said tent-structure, and constructed and arranged for permitting close approach between the reversely tapered adjacent sides of said tent-structure and inflated bags, substantially as described.
- 20 8. In an aerial navigation apparatus, the combination of a tent-structure comprising a floor, a central tube extending upwardly therefrom, stanchions extending upwardly from said floor toward each other and having 25 connection at their tops with said tube, a series of inflated bags located about said tent-structure and having connection with the lower part thereof, and an additional inflated bag above said tent-structure, and 30 a connection passing through said tube and connecting said additional inflated bag to said floor, substantially as described.
9. In an aerial navigation apparatus, the combination of a tent-structure comprising a floor, a central tube extending upwardly 35 therefrom, stanchions extending upwardly from said floor toward each other and having connection at their tops with said tube, a series of inflated bags located about said 40 tent-structure and having connection with the lower part thereof, an additional inflated bag above said tent-structure, a connection passing through said tube and connecting said additional inflated bag to said 45 floor, and a buoyancy-member located under said floor, substantially as described.
10. In an aerial navigation apparatus, the combination of an inflated buoyancy bag
- whose upper and lower ends taper oppositely, a parachute member provided with 50 an aperture in its top through which said tapering upper end of said inflated buoyancy bag is received to substantial extent, said parachute member increasing in diameter toward its lower end, the lower portion 55 of said parachute member being received about the downwardly tapering lower end of said inflated buoyancy bag, and constructed and arranged for forming a buoyancy chamber between said inflated buoyancy bag and parachute member, the upper end 60 of which is arranged to be opened by adjustment of elevation between said inflated buoyancy bag and parachute member and under maintenance of inflation of said inflated buoyancy bag, substantially as described.
11. In an aerial navigation apparatus, the combination of a tent-structure comprising a floor, stanchions extending upwardly 70 therefrom toward each other and a covering about said stanchions for forming a chamber thereunder, a series of inflated bags located about said tent-structure and having connection with the lower part of the same, 75 an elevated inflated buoyancy member and an elevated parachute member having an aperture therein in which said elevated inflated buoyancy member is received, flexible connections between said last-named members and said tent-structure for controlling the relative elevation between said members, and an intermediate inflated buoyancy bag having connection with said tent-structure and located above said tent-structure 80 and below said elevated inflated buoyancy member, substantially for the purpose described.
- In testimony whereof, I have signed my name hereto in the presence of two subscribing witnesses. 90
